BABY HOLDER FOR CHILDREN'S CHAIRS

Bernice Hlivka, Minneapolis, Minn.

Application June 15, 1950, Serial No. 168,271

2 Claims. (Cl. 227—49)

1

My invention relates to improvements in devices for holding a baby in a chair.

Baby holders heretofore devised for children's chairs have been inadequate in meeting the numerous requirements of a satisfactory article of such nature which call for a holder of relatively simple, durable, sanitary and inexpensive construction that is not only conveniently used and adjusted to fit a baby of any size, but also one that is comfortable to the baby and at the same time operable securely to hold the baby in the chair despite all of its efforts to get out of the chair.

The present device meets all of the said requirements desired in a satisfactory baby holder for a child's chair. It is constructed of washable fabric or other suitable flexible material in elongated formation and includes connected back and seat sections which are padded for the baby's comfort. Tie straps attached to the back section and adapted to be tied together about the back of the chair serve to hold said back section in place against the front of the chair-back. In continuation of the seat section is a crotch section and in continuation of said crotch section is an apron section. A waist strap for the apron section is medially secured at one edge thereof to the upper edge of the apron section and is adapted either to lie laterally extended from said apron section or laterally folded thereon in effect to shorten the apron. Sets of horizontally paired loops are applied to the front of the back section at different elevations selectively to receive the ends of the waist strap according to the baby's size, said ends of said waist strap being adapted to be tied together about the back of the chair, thereby snugly to girth the waist of the baby and hold the baby centered in the chair.

The bottom section and the apron section are each provided at each of its outer edges with a tab extending therewith. Each tab on the apron section is provided with an outer pair and an inner pair of fastener members and each tab on the seat section is provided with a series of fastener members along its outer edge. The fastener members of each of said outer and inner pairs thereof on each tab of the apron section are adapted selectively to coact with any two adjacent fastener members on the corresponding tab of the seat section to join the seat section and apron section snugly about the corresponding thigh of the baby adjacently above the knee in accord with the length and girth of the thigh.

In the accompanying drawing,

Fig. 1 is a plan view illustrating a baby holder embodying my invention and showing the holder as flatly spread out.

2

Fig. 2 is an edge view of the structure shown in Fig. 1.

Fig. 3 is a perspective front-quarter view showing the baby holder illustrated in Figs. 1 and 2 as applied to a child's chair.

Fig. 4 is a perspective rear-quarter view of the baby holder and chair shown in Fig. 3.

Referring to the drawing, it will be seen that the embodiment of my invention therein illustrated consists of an elongated holder A including a back section 10, a seat section 11 in continuation of said back section, a crotch section 12 in continuation of said seat section, an apron section 13 in continuation of said crotch section, and a waist strap 14 intermediately joined at one edge thereof to the free or upper end of the apron section 13. In the form of baby holder illustrated, I have shown the end portions of the waist strap 14 constituted as by terminal pieces 14a of tape-like material. Although not necessary, this means of acquiring the desired overall length in said waist strap 14 has been found to be advantageous in the manufacture of the holder. Preferably, the holder A will consist of two sheets 15, 16 of fabric or other suitable flexible material stitched one upon the other, the material being such that it can be readily cleansed with a dampened wiping cloth. Optionally a marginal binding strip, as at 17, and a decorative ruffle, as at 18, may be stitched to the sheets of material 15, 16. The back-section 10 and the seat section 11 are padded with a suitable filling material 19 placed between the two sheets of flexible material 15, 16 making up the device proper.

Placed in a child's chair, as in the chair shown at B, the back section 10 of the baby holder A rests against the forward side of the chair-back 20 and the seat section 11 of the holder rests upon the chair-seat 21. For thus holding said back-section 10 in place, it is supplied with a pair of tie straps 22 secured thereto at its edges intermediate the ends thereof, said straps 22 being adapted to be passed around the back 20 of the chair and knotted together at the rear thereof as seen in Fig. 4.

Ordinarily, upon placing a baby in the holder A, the crotch-section 12 and apron section 13 will be draped down in front of the chair B. Having seated the baby on the seat section 10 of the holder A, the apron section 13 will be lifted into position somewhat as shown in Fig. 3 with the crotch section 12 of the holder between the legs of the child.

For coaction with the free ends of the waist strap 14, I have provided at the front of the back section 10 upper and lower sets 23, 23a of horizontally paired loops 24, 24a, the same con-

sisting of two straps 25 located in spaced apart parallel relationship extending lengthwise of said back section 10 and fastened at their ends and intermediately thereof to said back-section as by stitching 26 or other suitable means. The ends 10 of the waist strap 14 are passed through their corresponding loops 24 or 24a of one or the other of the horizontally paired sets 23, 23a thereof from the inner sides of the loops. Thence said ends of said waist strap 14 are oppositely passed around the back 20 of the chair B and knotted together at the rear thereof as shown in Fig. 4. The lower set 23a of loops 24a are positioned approximately at the elevation of the arms 27 of the chair B so that the ends of the waist strap 14 running through either of the sets 23, 23a of loops 24, 24a may be passed under the chair-arms 27 before tying said ends of said waist strap 14 about the back 20 of the chair, thereby to thwart the rising of a baby from its safely seated position on the seat 21 of the chair.

The waist strap 13 may be laterally folded upon the upper marginal portion of the apron section 13 or unfolded and laterally extended, as shown in Fig. 3, in effect to shorten or lengthen said apron section 13. Having regard to the size of the child to be held in the holder A, appropriate choice of said folded or unfolded disposition of the waist strap 14 and appropriate choice of sets 23 of the horizontally paired loops 24 through which the ends of the waist strap 14 are to be passed will result in locating the waist strap 14 at the baby's waist line while snugly yet comfortably fitting the apron section 13 lengthwise thereof to the infant's body, whatever its size.

The seat section 11 of the holder A is formed at each of its outer edges with a tab 28 extending therealong and, likewise, the apron section 13 is formed at each of its outer edges with a tab 29 extending along the same. Each tab 29 of the apron section 13 is provided with an outer pair 30 of male snap fastener members 31 and with an inner pair 30a of similar fastener members 31a and each tab 28 of the seat section 11 is provided with a series of female snap fastener members 32 extending therealong. The outer pair 30 of fastener members 31 and the inner pair 30a of fastener members 31a on each tab 29 of the apron section 13 are engaged selectively with any two of the fastener members 32 on the corresponding tab 28 of the seat section 11 to join said apron section and seat section snugly about the corresponding thigh of the baby, whatever its size, always above the knee and adjacent thereto.

From the foregoing it will be readily comprehended that my improved baby holder may be comfortably fitted to a baby of any size and altered in the fitting thereof in conformity with the development of the child until it outgrows the need of such a holder. Said holder properly fitted to a baby will harness the child in seated position in a chair securely against any effort it may make to slide out of the chair or to stand up therein and thereby endanger its toppling from the chair. In thus protecting the baby against falls, the waist strap 14 holds the baby against the back section 10 of the holder A and down in the chair. Also, it holds said back section 10 against the back 20 of the chair B similarly to the tie straps 22 on said back section 10 which serve such purpose prior to the placing of a baby in the holder as well as after the baby is placed therein. With said waist strap 14 drawn about the waist of the baby through one of the

sets 23, 23a of loops 24, 24a under the arms 27 of the chair B and with the apron section 13 snugly tight lengthwise thereof and the thigh embracing portions of said apron section 13 and said seat section 11 snugly tight about the thighs of the baby above the knees, the child is unable to draw its knees into the holder in any effort made to stand in the chair by getting its feet on the seat of the chair.

Changes in the specific form of my invention, as herein described, may be made within the scope of what is claimed without departing from the spirit of my invention.

Having described my invention, what I claim as new and desire to protect by Letters Patent is:

1. A baby holder for a child's chair, the same being constructed of flexible material in elongated formation and comprising a back section, a seat section in continuation of said back section, a crotch section in continuation of said seat section, an apron section in continuation of said crotch section, tie means at the upper portion of the apron section for securing the same to the back of the chair and snugly about the waist of the baby, fastening elements at each of the outer marginal portions of the apron section, fastening elements at each of the outer marginal portions of the seat section, the fastening elements of one section being spaced apart laterally of the holder and the fastening elements of the other section being spaced apart longitudinally of the holder, the fastening elements at each marginal portion of one of said sections being cooperable selectively with the fastening elements at the corresponding marginal portion of the other of said sections adjustably to join said seat and apron sections snugly about the outer side of corresponding leg of a baby at the thigh.

2. A baby holder for a child's chair, the same being constructed of flexible material in elongated formation and comprising a back section, a seat section in continuation of said back section, a crotch section in continuation of said seat section, an apron section in continuation of said crotch section, means for adjustably fastening together the corresponding outer marginal portions of said apron section and seat section to join them snugly about the outer side of the corresponding leg of the baby at the thigh, tie straps extending from opposite sides of the waist portion of the apron section, loops disposed in pairs adjacently to one another longitudinally of the back section at the front thereof, the loops of each pair being respectively disposed adjacent opposite side edges of said back section, said tie straps being adapted to be threaded through their corresponding loops of that pair thereof selected in accord with the adjustment made in fastening the marginal portions of the apron section to the marginal portions of the seat section, said tie straps being adapted thence to be drawn about and tied to the back of the chair securing the holder in the chair and snugly girdling the apron section and back section of said holder about the waist of the baby.

BERNICE HLIVKA.
